L. MATTHEWS,

Rotary Steam Engine.

No 19967

Patented Apr. 13, 1858.

Fig. 1.

UNITED STATES PATENT OFFICE.

LEVI MATTHEWS, OF ANTRIM, OHIO, ASSIGNOR TO HIMSELF AND J. K. ANDREWS, OF SAME PLACE.

ROTARY STEAM-ENGINE.

Specification of Letters Patent No. 19,967, dated April 13, 1858.

To all whom it may concern:

Be it known that I, LEVI MATTHEWS, of Antrim, in the county of Guernsey and State of Ohio, have invented a certain new 5 and useful Improvement in Rotary Engines to be Propelled by Steam or other Gas or Fluid, of which the following is a full, clear, and exact description, reference being had to the accompanying drawing, which forms 10 part of this specification, and in which—

Figure 1 represents a sectional plan, mainly through the line $\alpha\alpha$ in Fig. 2, the cylinder and valve box covers being removed; and Fig. 2 represents a vertical 15 section, mainly through the line $\beta\beta$ in Fig. 1.

My improvement has reference to that class of rotary engines in which, "the steam is confined in a close and rigid chamber and acts on a solid and inflexible surface, 20 and makes its escape by confined passages, so that its full effect may be obtained in useful work." In engines of this character, either the revolving piston is made to have a radial action when passing the "abutment" in the cylinder, or the abutment is made to move out of the way for the passage of the piston in its circular travel. I here adopt the latter mode of operation and effect the occasional movement of the abut- 25 ment by a revolving stud acting on a lever connected with the abutment, as usual for such purpose; but the mechanism for operating the abutment may be variously modified, and be duplicated or adapted to work 30 the abutment in reverse directions of the piston's travel, which provision it has not been held necessary to show in the arrangement represented in the accompanying drawing, to avoid complexity in the explanation 35 of my improvement, for which reason also I have shown but one piston and sliding abutment operating in the same cylinder, but it will be obvious that two or more, if desired, may be used, also that the position 40 of the engine generally may be changed so as to produce a direct horizontal revolving motion instead of a vertical one as shown in the accompanying drawing, wherein the part marked A represents the cylinder 45 made with a circular groove or channel (a) in which the piston (B) works and which is intersected by a sliding abutment (C). The piston (B) is connected with a ring (D) suitably packed to prevent leakage and 50 forming an intermediate connection be-

tween the piston (B) and main shaft (E) to rotate the latter. On the main shaft (E) is a fly wheel (F) from which projects a stud (b) that in its circular travel (as indicated by the arrow γ in Fig. 1) strikes and acts on the back arm (c) of a beam (G) whose fulcrum pin (d) works with it. The front end of this beam is connected by rod (e) with the abutment (C), and the general arrangement is such that on the stud 60 (b) striking in an easy manner and gradually closing the back arm (c) of the beam, the abutment (C) is slid outward to admit of the piston (B) passing it, the stud (b) being so pitched relatively to the piston as 65 to act thus upon the abutment as the piston approaches and while passing it. A spring (f), acting on an arm (g) attached to the fulcrum pin of the beam, serves to close the abutment after the stud (b) has passed the 70 back arm of the beam, or the stud may be made to close the abutment by acting on a suitably formed extension of the back arm (c) of the beam, but the spring accomplishes 75 the result in a more rapid and easy manner 80 without violent jar. The steam is admitted to act upon the piston (B) through an aperture (h) in the cylinder on one side of the abutment, and escapes after having performed its duty, through an aperture (i) 85 on the other side of the abutment, the one aperture (h) forming a communication with 90 an inlet pipe (k), valve box (J) and steam pipe (m); and the other aperture (i) communicating with an escape pipe (n).

The annular cylinder (A) I make of circular form in its transverse section, and use a round piston (B) to match, which form of piston may be more readily packed than one of rectangular shape and dispenses with all 95 angles or corners that are liable to "cut," "bind" and produce leakage. The cylinder (A) thus shaped, is made say in two equal parts to admit of the introduction of the piston, the one part forming a lid or cover and 100 the two parts bolted together after the piston is inserted.

I connect the piston (B), with the ring (D) that conveys the motion to the main shaft, by hinging it (or rod extension of 105 said piston) to a piece (r) which forms a projection from the ring into the annular steam space of the cylinder. This mode of connection gives a free and easy action to the piston in its travel that greatly assists 110

the accommodating action of the packing, prevents imperfection in the construction of the cylinder or unequal wear of the revolving parts from producing much serious drag or occasional binding, and is in many respects more advantageous than a rigid connection, while its solidity as a driver is not impaired. The round shape of the piston and doubly round configuration of the steam channel in which it works make this hinged connection more advantageous and easy of operation than it otherwise would be.

To reduce or prevent loss of steam when the piston (B) is passing the inlet and outlet apertures (*h i*) and the abutment (C) is open or while it is being opened and closed, I cause the same motion that operates the abutment, by means of a valve (*s*), valve rod arm (*t*), rod (*u*) and arm (*v*) connected with the fulcrum pin of the beam (G), to shut off the supply of steam as the piston approaches the abutment and passes it and the inlet and outlet apertures on either side of it, and to let on the supply again after the piston has thus passed and the abutment is completing its closing action. This valve may be of varied construction and arrangement. It is here shown as situated in a separate valve box or steam chest (J) to which steam is admitted by a pipe (*m*) through an orifice (*m.¹*) and the valve opening and closing, at the periods just mentioned, over an orifice (*m.²*) that communicates with the inlet pipe (*k*); and the rod (*u*) that operates said valve is hooked on to the valve rod arm (*t*) so that it may be disconnected therefrom at pleasure to admit of the same valve being used by hand to start and stop the engine. But of course an additional starting and stopping valve may be used if preferred, and the valve, whose main object here has before been adverted to, may be a slide or throttle form of valve situated in the inlet pipe and either capable of disconnection or not for operation by the hand.

It has before been specified, that the round shape of the piston and doubly circular con-

figuration of the steam channel, in which the piston works (not a new construction in itself), makes the hinged connection of the piston more advantageous and easy of operation than it otherwise would be. But this is not all. The hinged connection of the piston (B) with the driving ring (D) is, it will be perceived, central in relation to the piston, by means of a rod or link that projects from the piston's center hitching on to, in a loose or free manner, the piece (*r*) which is a rigid attachment to the ring (D) and projects within the annular steam space of the cylinder. In this way, the steam, in its action on the piston's face, presses equally on either side of, or all around, the piston's central attachment to the rigid piece (*r*) which carries it, and the self accommodating action of the piston is in no wise restrained by pressure of the steam on one side only of the hinged attachment; tilting or twisting and binding of the piston is prevented; the greatest freedom of action generally secured, in the simplest possible manner; and all outside jointed connection, with the piston inside, done away with. This feature, though apparently small, is of considerable practical importance in the action of the engine.

While not claiming as new, or broadly, a hinged connection of the piston with the revolving or driving ring, by jointed attachment or attachments;

I do claim, as both new and useful,

Hinging the circular piston (B) at its center to the outside driving ring (D), by means of a rigid arm or piece (*r*) projecting from said ring into the annular steam channel of the cylinder, as and for the purposes set forth.

In testimony whereof, I have hereunto subscribed my name.

LEVI MATTHEWS.
